(57) **CLAIM**

The ornamental design for a set of motorcycle engine guards, as shown and described.

DESCRIPTION

FIG. 1 is a front perspective view of a set of motorcycle engine guards, showing my new design;

FIG. 2 is a rear perspective view thereof;

FIG. 3 is a front view thereof;

FIG. 4 is a rear view thereof;

FIG. 5 is a right side view of the left-hand bar, shown separately for ease of illustration thereof;

FIG. 6 is a left side view of the left-hand bar, shown separately for ease of illustration thereof;

FIG. 7 is a right side view of the right-hand bar, shown separately for ease of illustration thereof;

FIG. 8 is a left side view of the right-hand bar, shown separately for ease of illustration thereof;

FIG. 9 is a top view thereof; and,

FIG. 10 is a bottom view thereof.

The broken lines in the drawings illustrate the portions of the set of motorcycle engine guards, which form no part of the claimed design.

1 Claim, 10 Drawing Sheets
